UNITED STATES PATENT OFFICE.

JAMES H. BAKER, OF ALLEGHENY, ASSIGNOR TO THE BAKER FORGE COMPANY, OF ELLWOOD CITY, PENNSYLVANIA.

DESIGN FOR A BOX-STRAP BOLT.

SPECIFICATION forming part of Design No. 24,638, dated August 27, 1895.

Application filed March 5, 1895. Serial No. 540,667. Term of patent 7 years.

To all whom it may concern:

Be it known that I, JAMES H. BAKER, a citizen of the United States, residing at Allegheny, in the county of Allegheny and State of Pennsylvania, have invented and produced a new and original Design for Box-Strap Bolts; and I do declare the following to be a full, clear, and exact description of the invention, reference being had to the accompanying drawing, and to the letters and figures of reference marked thereon, which forms a part of this specification.

The figure is a perspective view of a box-strap bolt with my design forged thereon.

The leading feature of my design consists in two ribs or raised parts *b b*, having a common base and uniting at *a*, with an open space or field *c* between them. The hole through

the bolt *b* in the field *c* it may sometimes be desirable to place above the point where the ribs unite.

This design imparts a finished look to the article, which is commonly used in a conspicuous place on the outside of a wagon-body, making it important that it should have an attractive appearance.

I claim—

The design for a box strap bolt substantially as herein shown and described.

In testimony whereof I affix my signature in presence of two witnesses.

JAMES H. BAKER.

Witnesses:

A. H. CLARKE,
A. M. THOMPSON.
